UNITED STATES PATENT OFFICE.

ARTHUR WILLIAM BERSCH, OF MILWAUKEE, WISCONSIN.

MEASURING SCOOP.

Application filed June 13, 1925. Serial No. 36,821.

To whom it may concern:

Be it known that I, ARTHUR WILLIAM BERSCH, a citizen of the United States, residing at Milwaukee, county of Milwaukee, 6 and State of Wisconsin, have invented new and useful Improvements in Measuring Scoops, of which the following is a specification.

My invention relates to improvements in 10 measuring scoops for plastic materials such, for example, as ice cream.

The object of my invention is to provide means whereby the same device can be used for measuring different quantities.

More particularly stated, it is an object 15 of my invention to provide a measuring scoop for delivering quantities of ice cream for individual use in accordance with different standard prices, ordinarily referred 20 to as 5¢ and 10¢ helpings.

In the drawings:

Figure 1 is a side elevation of my improved measuring scoop as it appears in closed position preparatory to delivery of a 25 maximum quantity.

Figure 2 is a sectional view of the same, taken on line 2—2 of Figure 1, with dotted lines indicating the position of the parts when measuring a minimum quantity of 30 material.

Figure 3 is a sectional view drawn to the same plane as Figure 2 and showing the scoop spoons in open position.

Figure 4 is a sectional view drawn on 35 line 4—4 of Figure 2.

Like parts are identified by the same reference characters throughout the several views.

Scoop segments or spoons 1 are each 40 hinged at 2 to a suitable tubular headpiece 3 into which the tubular shank 4 is screwed. A plunger 5 extends upwardly through the shank 4 and headpiece 3 and at its upper end is provided with a bowl or bowl-shaped 45 ejector 6 which is preferably detachably mounted upon the reduced upper extremity of the plunger 5 to which it is screwed and locked by the nut 7. The portion 8 of the plunger is preferably enlarged to fit within 50 the head piece 3.

The lower portion of the shank 4 is telescopingly mounted in a handle sleeve 10 which is preferably provided with a knob 11 at its lower end. A spring 12 within the 55 sleeve 10 extends upwardly in the lower end of the shank 4 and bears against the lower

end of the plunger 5, thereby tending to push the plunger and bowl 6 outwardly to ejecting position.

A cross pin 15, anchored in the plunger 5, extends through short slots 16 in the sides of the tubular shank 4 and also passes through longer slots 17 in the handle 10, whereby, when the cross pin 15 is pulled downwardly toward the knob 11, it will first 60 move the plunger 5 downwardly until it engages the shank 4 at the lower ends of the slots 16. Thereupon, both the plunger 5 and the shank 4 may be drawn downwardly 65 into the handle sleeve 10 in unison. The intermediate portions of the spoons 1 are supported from the handle sleeve 10 by links 20 and therefore the continued downward movement of the cross pin 15 will cause the spoons 1 to close about the bowl 70 6 while the bowl and the hinge connections 2 are moving downwardly relatively to the handle sleeve 10. The lower ends of the links 20 are connected with the upper end of the handle sleeve 10 by a collar 21. 75

Collar 21 is provided with projecting ears 80 23 to which the lower ends of the links 20 are pivoted and each of the links is similarly pivoted to an intermediate portion of the associated spoon 1. 85

In operation, the bowl 6 and the spoons will be pressed downwardly into the material to be delivered while the spoons are in the open or spread position in which they are shown in Figure 3. Thereupon, the spoons 90 will be closed about the bowl by pulling the cross pin 15 in the direction of the knob 11. During this movement the spring 12 will be compressed by the plunger 5 which, together with the shank 4, will have a relative 95 movement in the direction of the knob 11. After the spoons have been closed about the bowl to substantially the position in which they are shown in Figure 1 the device will be raised from the container and the material engaged by the spoons, while closing, may then be ejected by releasing the cross pin 15 and allowing the spring 12 to push the bowl 6 upwardly and allow the spoons 1 to swing to the open position when the cross pin 15 engages the shank 4 at the upper 100 ends of the slots 16. 105

The quantity of material which will be engaged by these spoons 1, when closing about the bowl 6, will depend upon the relative position of the bowl while the spoons are being closed. The latter is adjustably support- 110

ed in either the full line position or the dotted line position of Figure 2. In the full line position it is supported by the headpiece 3 and the curvature of the lower portion of 5 each spoon is such that the spoon will substantially conform to and bear upon the outer surface of the bowl when in the closed position.

When the bowl 6 is adjusted to the dotted 10 line position of Figure 2 it may be supported in that position from the shank 4 by a hook 25 pivotally connected with the shank at 26 and adapted in one position of adjustment to engage underneath the cross pin 15 15 as shown in Figure 3 and as also shown by dotted lines in Figure 2. When the hook is engaged with the cross pin 15 the downward movement of the latter in the slots 16 is limited by the hook. Therefore, as soon as the 20 cross pin engages the hook, the plunger 5 and shank 4 will commence to move downwardly in unison and the spoons 1 will be caused to close about the bowl with the lower portions of the spoons spaced from the bowl 25 at a sufficient distance to measure the desired smaller quantity of material to be held to the bowl by the spoons in a position to be delivered when the spoons are swung to the open position as above described, and the 30 bowl moves to the ejecting position by recoil of the spring 12.

I claim:

1. A measuring scoop comprising the combination with an ejector, of a set of spoon 35 shaped scoop members adapted to close about the ejector and adapted for movement longitudinally relative to the axis of said ejector, a sleeve with which the scoop members are pivotally connected, a plunger 40 mounted to slide in the sleeve and supporting the ejector, and a handle in which the plunger and sleeve are seated.

2. A measuring scoop comprising the combination with an ejector, of a set of spoon 45 shaped scoop members adapted to close about the ejector and adapted for movement longitudinally relative to the axis of said ejector, a slotted sleeve with which the scoop members are pivotally connected, a plunger axially 50 movable in the sleeve and an operating piece connected with the plunger and extending through said slot.

3. A measuring scoop comprising the combination with an ejector, of a set of spoon 55 shaped scoop members adapted to close about the ejector and adapted for movement

longitudinally relative to the axis of said ejector, a sleeve with which the scoop members are pivotally connected, a plunger 60 mounted to slide in the sleeve, a socketed handle in which the sleeve is movably seated, a spring in the socket having one end seated against the plunger, and means for actuating the plunger with the sleeve and to a limited extent independently thereof.

4. A measuring scoop comprising a set of scoop members, a support separately pivoted to each of the scoop members to allow them to swing about their respective pivots and laterally of the closed position of said members, a movable piece within the space between the scoop members, adapted to determine the quantity of material to be engaged by the scoops, a suitable handle and an operating piece associated therewith and adapted 70 to actuate the scoop members.

5. A measuring scoop comprising the combination with an ejector, of a set of spoon shaped scoop members adapted to close about the ejector and adapted for movement 75 longitudinally relative to the axis of said ejector, a scoop member support in separate pivotal connection with said members, a handle linked to said scoop members, said support and handle being relatively movable to swing said members upon said pivotal connections and said ejector being also relatively movable with reference to both the handle and support, and means for varying the limitation of independent movement to 80 vary the quantity of material to be placed by scoops in a position for delivery by said ejector.

6. A measuring scoop comprising the combination with a handle having a tubular portion, of a set of spoon-shaped scoop members each having a fixed pivotal connection with said portion, and a movable member journaled in said tubular portion and movable longitudinally thereof, said scoop members 100 each being pivotally connected with said movable members.

7. A measuring scoop comprising the combination with a handle having a longitudinally extending portion, of a set of spoon-shaped scoop members each having a fixed pivotal connection with said portion, and a movable member pivotally connected with each of said scoop members and movable longitudinally of the extending portion of said 110 handle.

ARTHUR WILLIAM BERSCH.
